UNITED STATES PATENT OFFICE

2,593,160

WINDOW STRUCTURE

Lory Mancini, Los Angeles, Calif.

Application April 15, 1949, Serial No. 87,704

2 Claims. (Cl. 160—187)

1

This invention relates to new and useful improvements and structural refinements in windows, and the principal object of the invention is to provide efficient and conveniently controlled ventilation.

This object is achieved by the provision of the instant window structure which includes what may be called an articulated sash unit consisting of several panels swingable on horizontal axes, and an important feature of the invention resides in the provision of individually adjustable means for retaining the several panels in an open or partially open position.

Another feature of the invention resides in the structural arrangement of the panels whereby they may be folded one upon another if so desired, and a still further feature of the invention involves the provision of means for effectively sealing the joints between contiguous edges of the sash panels when closed, thus safeguarding against the passage of weather through the closed window.

Some of the advantages of the invention reside in its simplicity of construction, in its adaptability to convenient operation and cleaning, in its pleasing appearance, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is an inside elevational view of the invention;

Figure 2 is a cross sectional view, taken substantially in the plane of the line 2—2 in Figure 1;

Figure 3 is a group perspective view showing portions of the window frame together with top and intermediate sash panels;

Figure 4 is a group perspective view of showing a portion of the window frame together with intermediate and bottom panels;

Figure 5 is a fragmentary elevational view of one side of the window frame provided with a groove and a plurality of keeper pins;

Figure 6 is a fragmentary perspective detail showing one of the hooks on the bottom panel of the window;

Figure 7 is a cross sectional view, similar to that illustrated in Figure 2, but showing a modified embodiment of the invention in its closed position; and

2

Figure 8 is a cross sectional view of the subject shown in Figure 7 in a folded or open position.

Like characters of reference are employed to designate like parts in the specification and throughout the several views.

Referring now to the accompanying drawings in detail, more particularly to Figures 1—5 inclusively, the invention consists of a window structure designated generally by the reference character 10, the same embodying a rectangular frame 12 including a pair of spaced parallel side members 14 and a bottom member 16, this frame being adapted to accommodate an articulated sash unit designated generally by the reference character 18.

The sash unit 18 consists of a plurality of contiguous panels which extend transversely of the window opening, these panels being designated, for purposes of convenient identification, as the top panel 20, the intermediate panel 22 and a bottom panel 24.

The side edges of the top panel 20 and intermediate panel 22 are recessed adjacent the contiguous edges of the two panels to receive sets of plates 26, 28 respectively, these plates being secured in their recesses by suitable screws 30 and each plate being provided with a laterally projecting stud, namely, the stud 32 on the plate 26 and the stud 34 on the plate 28. The studs 32, 34 are rotatable in respective apertures 36, 38 provided in flat mounting plates 40, the latter, in turn, being secured by the screws 42 in suitable recesses with which the side members 14 of the frame 12 are formed (see Figures 1 and 3).

It will be apparent from the foregoing that the top panel 20 is swingable from its vertical closed position in the frame 12 to an open position illustrated by the phantom line 44 in Figure 2, while the intermediate panel 22 is similarly swingable to an open position illustrated by the phantom line 46.

A suitable latch 48 (see Figure 1) may be provided on the upper edge portion of the top panel 20 for retaining this panel in its closed position, and a length of chain 50, or the like, may be secured to the frame and to the top member 20 for the purpose of restricting the opening movement of the latter, as will be clearly apparent.

The side members 14 of the frame 12 are provided with vertically extending grooves 52 and a plurality of vertically spaced keeper pins 54 extend transversely of these grooves, as is best shown in Figure 4. A pair of keeper arms 56 are pivoted as at 58 to the side edges of the interme-

diate panel 22, these arms being engageable selectively with the keeper pins 54 for the purpose of adjustably retaining the panel 22 in its open position, independently of the top panel 20. When the panel 22 is closed, the arms 56 are received in suitable recesses 68 provided in the side edges of the panel 22, and it is to be noted that the keeper arms 56 may be adjusted on the pins 54 in such manner that the panel 22 is supported in a substantially horizontal position, thus facilitating lowering of the top panel 20 to a superimposed position on the panel 22 after disconnecting the chain 50.

As is best shown in Figure 2, a weatherstrip 62 is provided at the lower edge of the panel 20 to cover the contiguous edges of the panels 20, 22, which are rounded or arcuated as at 64 so that inward opening of the panels is facilitated but the weather is effectively excluded from passing through the window when closed.

The bottom panel 24 is provided in the sides thereof adjacent its upper edge with suitable recesses to accommodate portions of flat links 66 which are pivoted by suitable screws 68 to the panel 24 and extend upwardly therefrom, their upper portions, in turn, being formed with slots 70 to accommodate additional screws 72 whereby these links and the panel 24 are connected to the lower edge portion of the intermediate panel 22.

It will be apparent from the foregoing that when the intermediate panel 22 is opened, the links 66 will cause the bottom panel 24 to be opened concurrently, and means are provided for preventing the bottom panel from swinging freely when in its open position, these means consisting of a pair of hooks 74 which are secured as at 76 to the lower edge portion of the bottom panel 24 and are engageable selectively with the aforementioned keeper pins 54 when the bottom panel is in its open position, as indicated at 78 in Figure 2. When the bottom panel is closed, the hooks 74 are simply received in suitable recesses 80 provided in the bottom member 16 of the frame 12.

In order to safeguard against the passage of weather through the closed window, the contiguous edges of the panel 22, 24 are complementarily beveled as indicated at 82 in Figure 2, and it should be explained that the purpose of the slots 70 in the links 66 accommodating the screws 72 is to enable these complementarily beveled, contiguous edges of the panels 22, 24 to be spread apart when the panels are opened, after which the bottom panel 24 may be swung upwardly to a superimposed position on the intermediate panel 22, as indicated by the phantom line 84 in Figure 2. Needless to say, this arrangement is employed when it is not desired to secure the bottom panel 24 by engaging the hooks 74 with the keeper pins 54.

It will be apparent from the foregoing that the several panels of the sash unit may be quickly, easily and conveniently adjusted so as to properly control ventilation through the window opening. Moreover, since the sash panels are swingable or openable inwardly, cleaning thereof is greatly facilitated. If desired, co-acting latch members 86, 88 may be provided on the bottom panel 24 and one of the frame members 14 respectively, these latch members facilitating locking of the bottom panel 24 to prevent its opening, and since the intermediate panel 22 cannot be opened without opening the bottom panel 24, the latch members 86, 88 effectively function to prevent un-

sired opening of both the intermediate and the bottom panel.

A suitable screen 90 may be provided in the frame 12 on the outside of the sash unit for obvious reasons.

Finally, it should be understood that the panels 20, 22, 24 consist of suitable perimetric frames equipped with transparent panes, in accordance with conventional practice.

Referring now to the accompanying Figures 7 and 8, these figures illustrate a modified embodiment of the invention designated generally by the reference character 100, the same being similar to the embodiment already described and consisting of a frame 102 provided with an articulated sash unit 104.

However, this sash unit, rather than consisting of only three panels, consists of four panels, namely, the top panel 106, the upper intermediate panel 108, the lower intermediate panel 110 and the bottom panel 112. The structural arrangement and mounting of the panels 106 and 108 is similar to that of the aforementioned panels 20, 22, but the bottom panel 112, rather than being connected to the panel 108, is connected by the links 114 to the lower edge portion of the lower intermediate panel 110, the upper edge portion of which, in turn, is connected to the lower edge of the upper intermediate panel 108 by means of a suitable hinge 116.

The side members of the frame 102 are again provided with vertical grooves 118 and vertically spaced keeper pins 120, while the panels 108, 112 are equipped with the respective arms and hooks 122, 124 which are engageable independently and selectively with the pins 120 for the purpose of adjustably retaining the several panels in their open position. However, it is to be noted that by virtue of the hinge 116 and links 114, the panels 110, 112 may be folded in a superimposed relation on the open panel 108, as shown in Figure 8.

The contiguous edges of the panels 108, 110 and the contiguous edges of the panels 110, 112 are complementarily beveled as indicated at 126, 128 respectively, while contiguous edge portions of the panels 106, 108 are rounded or arcuated as at 128.

It is believed that the advantages and use of the invention will be clearly apparent from the foregoing disclosure and accordingly, further description at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a window structure, the combination of a frame, and an articulated sash unit mounted in said frame and including a top panel, an intermediate panel and a bottom panel, pairs of laterally projecting studs provided adjacent the respective lower and upper edges of the top and intermediate panels and rotatably journaled in opposite sides of said frame, a pair of links pivotally mounted at the opposite sides of the intermediate and bottom panels and swingably connecting the same together, and means for sustaining said panels in an open position.

2. The structure as defined in claim 1 wherein said intermediate panel consists of upper and

2,593,160

5

lower sections having contiguous edges hinged together, a pair of said studs being provided on the upper section and said links being pivoted to the lower section of said intermediate panel.
